METHOD OF MAKING A VALVE

Application filed March 18, 1927. Serial No. 176,448.

This invention relates to valves and particularly to the poppet type of valve which is used in internal combustion engines.

One object of the invention is the provision of a method of manufacture by which a hollow valve of this type containing a quantity of cooling medium may be cheaply and conveniently constructed.

Another object of the invention is the provision of a method of manufacturing engine poppet-valves which contain a quantity of cooling medium, so that the valve may be permanently closed to obtain a pressure-tight seal and insure the retention of the cooling medium within the valve.

A further object of the invention is the provision of a hollow valve having a portion swaged together and closed in such a manner as to permanently and perfectly seal the cooling medium in the valve.

Further objects and advantages of the invention will be more fully set forth in the following description and in the accompanying drawings in which—

25 Figs. 1 to 4 show the successive steps taken in the manufacture of a valve, Fig. 1 showing in section the first step of the process, Fig. 2 showing the stem end of the valve swaged together, Fig. 3 showing the stem end after the machining operation has taken place, and Fig. 4 showing the completed valve in section.

Fig. 5 is a central section through a modified form of construction.

35 In the manufacturing of poppet valves used in internal combustion engines it has been proposed to construct the valve so that it is provided with a hollow interior which is partly filled with a cooling medium, so that the heat from the head end of the valve may be conducted in an efficient manner to the stem where it may be more readily dissipated. By the use of such a construction the excessive 40 heat attained at the head end of the valve, especially where the valve is used to regulate the exhaust of the engine, may be quickly conducted away from the hot end so that the valve may operate at a comparatively cool 45 temperature. It has been proposed to partly

fill the stem of the valve with a mixture of salts of potassium nitrate and sodium nitrate, and one composition of a cooling medium is 55% potassium nitrate and 45% sodium nitrate. Such a mixture of salts of the alkali metals has a melting temperature of about 425 degrees F. which is well below the working temperature of the portions of the valve with which the medium is in contact. The salt mixture just mentioned is intended to be 60 merely an example of a suitable cooling medium which may be provided within the valve. It has been found desirable to permanently seal the cooling medium within the hollow valve so that the high temperatures and the 65 rapid motion and impacts to which the valve is subjected will not cause the loss of any of the cooling medium. In accordance with the invention which will now be described the end of the valve may be permanently and perfectly sealed so as to effectively retain the 70 cooling medium in the valve.

Referring now to the accompanying drawings by reference numerals in which like numerals designate corresponding parts in various views, Fig. 1 shows a metal valve part which is constructed as the first step of the process. This valve part designated generally 10 is comprised of a head 11 and the stem 12. This stem is hollow, and within its entire length is an interior bore 13 which extends substantially up and into the head of the valve. Adjacent the open end of the stem the valve walls are enlarged and thickened at 14, the enlarged portion increasing gradually as shown at 15 and 16 from the thinner portions of the stem wall at each side of the enlargement. The interior bore 13 is of a constant diameter from the open end 17 to the head end 18 of the valve. The metal valve part shown in Fig. 1 is machined in any desired manner so that it takes the form shown in this figure. The interior bore may conveniently be made by a drilling operation.

The wall at the stem end of the valve is then drawn together in a concentric manner and this may preferably be done by drawing or swaging the enlargement 14 from point 15 to 16 so that the interior of the valve at this locality is very considerably restricted, only 100

a small longitudinal central passage 25 being left after the swaging operation is completed. Since the surfaces 15 and 16 interconnecting the enlargement 14 and the thinner portions 5 of the stem of the valve adjacent thereto are conically tapered in a gradual manner as shown, the outside of the stem of the valve will be substantially of a uniform diameter after the swaging operation just mentioned 10 has been completed.

After the stem end of the valve has been substantially closed together by the swaging operation mentioned the end of the valve is machined so that a groove 30 is provided to 15 receive the customary collet or other spring retaining device. At the same time the outside diameter of the valve is machined to the proper size. The very restricted central longitudinal opening 25 is then enlarged by a 20 drilling operation so that a bore 31 of a definite desired size is provided in the end of the valve as shown in Fig. 3. The outer end of this end bore 31 is counter-bored at 32 to provide a tapering surface at this point. The 25 end surface 33 is machined so that the valve is of suitable length.

After the machining operation completes the form of the end of the valve stem the proper amount of cooling medium is supplied 30 to the interior of the valve. In case a sodium nitrate and potassium nitrate mixture is to be used as a cooling medium these substances are supplied in the form of a powder through the opening 31 in the stem end of the valve. 35 This opening 31 need only be of sufficient size so that the salts or other cooling medium may be conveniently supplied. After the metal salts or other cooling medium has been supplied to the interior of the valve in the proper 40 amount so that the valve may be efficiently cooled, a metal plug 35 is forced into the hole 31 in the end of the valve. After the plug 35 is in place the end portion 36 which has been previously counter-sunk is filled in by welding, a good wearing material being utilized 45 for this purpose. The weld 37 permanently and perfectly seals the end of the valve stem in a pressure-tight manner and effectively retains the cooling medium within the valve 50 so that its loss is absolutely prevented. The plug 35, which may if desired be slightly tapered to provide for its convenient insertion, prevents the arc and the heat of the weld from coming into direct contact with the cooling salts and permits the convenient handling 55 of the valve during the welding operation.

By swaging the walls of the valve together as shown in Fig. 2 the weld which closes the end of the valve may be made of a minimum 60 size. It is desirable to have a minimum amount of material added by the weld so that the possibility of an unsecure weld or of a leaky connection at the weld will be minimized. However, it is undesirable to com- 65 pletely swage the open stem end of the valve

together as the central passage 25 may only be perfectly closed with great difficulty.

Instead of providing the cooling medium within the valve after the swaging and subsequent re-boring of the end of the stem has been completed, the cooling medium may be inserted in the open end of the valve before the swaging operation takes place. With the valve having the form as shown in Fig. 1 therefore, the proper amount of cooling material is added and the valve is then heated to above the freezing temperature of the cooling medium. During this heating process of course, the head end of the valve is kept down so that the loss of the material is prevented. The heating of the valve has the effect of liquefying the cooling material, and when the valve is subsequently cooled this cooling material is retained in a solid state in the head end of the valve. The open stem end of the valve may then be swaged together as previously described and the stem end may be machined as shown in Fig. 3 to receive the plug 35 and permit the later welding of the center of the end surface of the valve. It is unnecessary, however, to re-bore the central passage after the swaging operation has been completed if the cooling medium has already been placed in the valve. The swaging of the stem end of the valve may be completed in such a manner that the central passage through the end of the valve is substantially closed. To insure the complete and permanent sealing of this central passage the end of the valve at the very center portion may be spot-welded as by the use of an acetylene torch.

As shown in Fig. 5 the stem end of the valve has been practically completely swaged together along the line 40. In the construction of a valve as shown in Fig. 5 the cooling medium as indicated at 41 and which may consist of the mixture of potassium and sodium salts previously mentioned is supplied to the interior of the valve before the swaging operation is started. The metal valve part as shown in Fig. 1 is therefore filled with the desired amount of cooling medium 41 and the valve heated to cause the liquefying and subsequent solidifying of the cooling medium in the head end of the valve. The stem portion 42 is then swaged together during which the solidified cooling material is retained in the head end of the valve. The collet receiving groove 43 may then be machined in the stem end of the valve and this stem cut off to the desired length by machining the end surface 44. This surface is preferably made perfectly flat and to it is welded a flat valve tip 45 so that the butt-weld by which the fastening of the tip 45 is effected is of a maximum area. The area of contact of the weld or joint at the valve tip is substantially the same as the entire cross-sectional area of the valve since the restriction 130

at 40 is of a negligible size. The weld is thus exceedingly strong and serves to effectively and permanently seal the small open end of the restriction 40 and to firmly attach 5 the tip in place. The tip 45 is preferably constructed of a material which may receive the impact and pounding of the cam by which the valve is operated. The main portion of the valve may be made of iron or steel of 10 a suitable composition so that the swaging operation may be conveniently effected and so that the head end of the valve may resist the heat to which it must be subjected. The tip 45 has been shown of comparatively small 15 length but it is unnecessary to cause the joint between the tip and the swaged end of the valve to be between the valve end and the collet 43. This depends upon the particular circumstances and upon the different materials 20 from which the tip and the main valve operation are constructed.

While the methods herein described constitute preferred embodiments of the invention, it is to be understood that the invention is not 25 limited to these precise methods, and that changes may be made in them without departing from the scope of the invention which is defined in the appended claims.

What is claimed is:

30 1. The method of making a valve for internal combustion engines comprising making a metal valve part embodying a valve head and a valve stem formed integrally therewith and having an enlargement adjacent the stem end, machining a hole in the stem from the stem end, and swaging the stem end together.

2. The method of making a valve for internal combustion engines comprising making 40 a metal valve part embodying a valve head and a valve stem of one piece construction and having an enlargement adjacent the stem end, drilling a hole in the stem from the stem end thereof, drawing the stem end concentrically together to restrict the opening, and permanently sealing the restricted opening.

3. The method of making a valve for internal combustion engines comprising making 45 a metal valve part having a hollow stem open at the stem end and having an enlargement adjacent the stem end, drawing the said end concentrically together, partly filling the hollow stem with cooling material, and then permanently and entirely closing the drawn 55 end.

4. The method of making a valve comprising 60 making a metal valve part having a hollow stem open at the stem end, swaging the stem end concentrically together to restrict the opening at the stem end, partly filling the hollow stem with cooling material, machining the end of the valve stem, and then closing the restricted opening so as to permanently seal the cooling material in a pressure tight 65 manner.

5. The method of making a valve comprising making a metal valve part having a hollow stem open at the stem end, drawing the stem end together concentrically, enlarging the central passage through the stem end, inserting a predetermined amount of cooling material through the enlarged passage, and then welding the end of the enlarged central passage to permanently seal the cooling material within the valve in a pressure tight 70 75 manner.

6. The method of making a valve comprising making a metal valve part having a hollow stem open at one end, drawing the open end of the valve so as to concentrically reduce the opening through the same, inserting a predetermined amount of cooling material within the hollow valve stem, heating the valve to cause the cooling material to be retained at the head end of the valve, and then permanently sealing the reduced opening in the end of the valve so as to retain the cooling material permanently within the hollow valve. 80 85

7. The method of making a valve comprising making a metal valve part having a hollow stem open at the stem end, inserting a predetermined amount of cooling material through the open end of the stem, heating the valve to liquefy the material within the valve, permitting the valve to cool to cause the solidification of the cooling material in the head end of the valve and then reducing the opening in the open end of the valve by drawing the said end together concentrically. 90 95 100

8. The method of making a valve comprising making a metal valve part having a hollow stem open at the stem end, inserting a predetermined amount of cooling material through the open end of the stem, heating the valve to liquefy the material within the valve, and permitting the valve to cool to cause the solidification of the cooling material in the head end of the valve, reducing the opening in the open end of the valve by drawing the said end together concentrically, and permanently closing the reduced passage through the end of the stem and machining the stem end of the valve. 105 110 115

9. The method of making an engine valve comprising making an integrally headed valve part, drilling the valve part from the stem end, partly closing in the end of the stem except for a small central opening much smaller than the internal diameter of the drilled hole, inserting a predetermined amount of cooling material through the central opening, welding the end of the stem to permanently seal up the small central opening and permanently seal the cooling material within the valve, and machining the valve. 120 125

In testimony whereof I hereto affix my signature.

ROBERT JARDINE.
